UNITED STATES PATENT OFFICE.

STEWART BURCHARD, OF BROOKLINE, MASSACHUSETTS.

DESIGN FOR A KNITTED BONNET.

No. 39,940.

Specification for Design.

Patented April 20, 1909.

Application filed February 13, 1909. Serial No. 477,823. Term of patent 7 years.

To all whom it may concern:

Be it known that I, STEWART BURCHARD, a citizen of the United States, residing at Brookline, in the county of Norfolk and State of Massachusetts, have invented a new, original, and ornamental Design for Knitted Bonnets, of which the following is a specification, reference being had to the accompanying drawing, forming part thereof.

The figure is a side view of a knitted bonnet showing my new design.

I claim:

The ornamental design for a knitted bonnet, as shown.

STEWART BURCHARD.
